UNITED STATES PATENT OFFICE.

FRANK J. ZECHER, OF LANCASTER, PENNSYLVANIA, ASSIGNOR TO THE
GREY IRON CASTING COMPANY, LIMITED, OF MOUNT JOY, PENNSYLVANIA.

DESIGN FOR A TOY BANK.

SPECIFICATION forming part of Design No. 29,686, dated November 15, 1898.

Application filed September 28, 1898. Serial No. 692,134. Term of patent 7 years.

To all whom it may concern:

Be it known that I, FRANK J. ZECHER, a citizen of the United States of America, residing at Lancaster, in the county of Lancaster and State of Pennsylvania, have invented and produced a new and original Design for Toy Banks, of which the following is a specification, reference being had to the accompanying drawings, forming part hereof.

The object of my invention is to produce a new and original design for a toy bank which shall provide the required receptacle for money or coin and by its peculiar shape and configuration present a convenient toy bank and one that will be ornamental and pleasing in its general appearance.

The shape and configuration of the bank is shown in the accompanying drawings and fully described in the following specification, the essential features upon which I desire protection being more particularly referred to herein.

In the drawings, Figure 1 is a side elevation of a toy bank, showing my new design. Fig. 2 is a plan view. Fig. 3 is a front elevation.

As shown in the drawings, the leading or material features of my design for a toy bank are characterized by a box or receptacle in

shape similar to the hull of a marine vessel or war-ship—that is, with vertical side walls 30 A, joined at their ends and curved outward longitudinally, and a flat top piece b between the side walls, round turret-like projections e e on top of the peculiar-shaped box or receptacle, near the front and rear ends thereof, and 35 having projections f in imitation of cannons, a military mast g, the rear or after turret-like projection having a coin-slot j extending across the top thereof, and a cylindrical projection or smoke-stack K, intermediately located.

The box or money-receptacle in accordance with my design is provided with an ornamental scroll l at its forward end, and the lower part of the rear end is curved in or depressed, 45 as shown at m, while the central portion has a circle or hole n and adjoining scrolls n' n'.

Having described my new and original design for toy banks, what I claim, and desire to secure by Letters Patent, is—

The design for a toy bank, substantially as herein shown and described.

FRANK J. ZECHER.

In presence of—

II. O. WILSON,
CHAS. R. KLINE.
